(57) CLAIM

The ornamental design for a vehicle grille crown, as shown and described.

DESCRIPTION

FIG. 1 is a front perspective view of a vehicle grille crown showing our new design;

FIG. 2 is a front elevational view thereof;

FIG. 3 is a left side view thereof, the right side view being mirror symmetrical to FIG. 3; and,

FIG. 4 is a top plan view thereof.

The broken line showing of the vehicle grille, in FIGS. 1-4, depicts environment and forms no part of the claimed design.

The rear and the bottom of the vehicle grille crown is unornamented.
